CLAIM

The ornamental design for a surveillance camera, as shown and described.

DESCRIPTION

FIG. 1 is a front perspective view of a surveillance camera showing our new design;

FIG. 2 is a front elevational view of the surveillance camera;

FIG. 3 is a rear elevational view of the surveillance camera;

FIG. 4 is a left side elevational view of the surveillance camera;

FIG. 5 is a right side elevational view of the surveillance camera;

FIG. 6 is a top plan view of the surveillance camera; and,

FIG. 7 is a bottom plan view of the surveillance camera.

The broken lines depict portions of the surveillance camera in which the design is embodied that form no part of the claimed design.
